G. L. H. & Co. ATTORNEY

Patented May 24, 1927.

UNITED STATES PATENT OFFICE.

MANUEL ALARCON, OF GALLUP, NEW MEXICO.

GYMNAStic TOY.

Application filed April 13, 1926. Serial No. 101,629.

This invention relates generally to toys, the invention having more particular reference to a manually operated toy.

The invention has for an object the provision of an adjustable manually operated toy.

A further object of the invention is the provision of a manually operated toy of simple and cheap construction.

For further comprehension of the invention, and of the objects and advantages thereof, reference will be had to the following description and accompanying drawing, and to the appended claims in which the various novel features of the invention are more particularly set forth.

Fig. 1, of the drawing, is a side elevational view of my improved manually operated toy.

Fig. 2, is a front elevational view thereof.

Fig. 3, is an enlarged fragmentary sectional view taken on the line 3—3 of Fig. 1.

Fig. 4, is a fragmentary perspective view thereof.

Fig. 5, is an enlarged perspective view of the adjustable block as used in connection with my improved manually operated toy.

Fig. 6, is an enlarged fragmentary front elevational view, showing the cross support as used in connection with my improved manually operated toy.

As herein embodied my improved manually operated toy comprises two vertical arms 10 and 11, having suitable lower elements 12 and 13, or handles, and attached by nails 14 and 15, or the like, respectively to the extremities of a cross support 16, at or near the upper portion of the said lower elements 12 and 13.

The upper extremities 17 and 18, respectively of the vertical arms 10 and 11, are provided with elongated slots 19 and 20 respectively, having a plurality of notches 21, oppositely located, and spaced somewhat closer together as further located from the said cross support 16.

The adjustable blocks 22, rectangular shaped, are provided with engaging members 23, attached thereto as at 24, by a dove-tail, or any similar suitable means, the said engaging members 23 being made of rubber, or any similar suitable material, and having extended portions 25, oppositely located, and of suitable shape and size to engage the notches 21 of the said upper extremities 17 and 18 of the said vertical arms

10 and 11. It being understood that the engaging members 23 are of suitable width to engage the said elongated slots 19 and 20, and that the adjustable blocks 22 are somewhat wider than the said engaging members 23.

The adjustable blocks 22 and the engaging members 23 are provided with apertures 26, located at or near the extremities thereof, to accommodate a flexible member 27, cord, string, or the like, which is passed through the said apertures 26, and the apertures 32 and 33 located above one another in the free extremities of the arms 28, of a figure, preferably that of an acrobat, comprising a body 29 and head 30, having said arms 28, and legs 31, pivotally attached thereto. It being clearly understood that the hereinbefore mentioned figure, may be that of a monkey, or any suitable figure, and that the said figure will be normally vertically supported from the said flexible member 27, as clearly shown in Fig. 4, of the accompanying drawing.

It will be further understood that the said cross support 16, will be provided with a slightly curved or relieved upper extremity, as designated by the reference numeral 34, to permit the vertical arm 10 to be rocked or tilted by pressing together and releasing the said vertical arms 10 and 11, which will cause the flexible member 27 to wind and unwind so as to impart acrobatic motion to the said figure, it being clearly understood that the said acrobatic motion may be increased by positioning the said engaging members in the said notches 21 further located from the said cross support 16.

While I have above described the preferred form, construction, and arrangement of the several elements employed, it will be understood that the device is, nevertheless, susceptible of considerable modification therein, and I therefore reserve the privilege of resorting to all such changes as may be fairly embodied within the spirit and scope of the invention as claimed.

Having thus described my invention, what I claim as new and desire to protect by Letters Patent of the United States is as follows:

1. A toy comprising substantially vertical arms, a cross support attached to said arms and disposed between the extremities thereof, said vertical arms being provided with

elongated slots, adjustable blocks engaging the elongated slots, means on said blocks for retaining the latter in an adjusted position, a flexible member attached to said adjustable blocks, and a figure threaded on said flexible member, said flexible member being adapted to be actuated by movement of the ends of said arms to impart acrobatic motion to said figure.

- 10 2. A toy comprising vertical arms, a cross support attached at its extremities to said vertical arms, the upper extremities of the said vertical arms being provided with elongated slots having a plurality of notches oppositely located, and spaced closer together as further located from the said cross support, adjustable blocks mounted on the side of said vertical arms, engaging members attached to said blocks by a dovetail, said engaging members having extended portions oppositely located to engage the said notches, said adjustable blocks and said engaging members provided with apertures located at the extremities thereof to accommodate a flexible member, which is passed through apertures located above one another in the free extremities of the arms of a figure comprising a body and head, having said arms and legs pivotally attached thereto, so as to

support the said figure in a normally vertical position, said cross support provided with a curved extremity to permit one of the said vertical arms to be rocked by pressing together and releasing the said vertical arms, to cause the said flexible member to wind and unwind, so as to impart acrobatic motion to the said figure.

3. A toy comprising vertical arms, a cross support having rounded ends attached at its extremities to said vertical arms, said vertical arms having slots therein, adjustable members comprising means for retaining a fixed position of adjustment associated with said slots, a flexible member attached to said adjustable members and movable therewith, and a figure journaled on said flexible member adapted to be actuated by movement thereof for producing acrobatic motion, said adjustable members being adapted to be positioned substantially at the extremities of said vertical arms for increasing the actuation of said figure and to be positioned at the lower ends of said slots for decreasing said actuation.

In testimony whereof I have affixed my signature.

MANUEL ALARCON.
